HAND GRINDER

W. Arthur Ernst, Racine, Wis., assignor to Howard Industries, Inc., Racine, Wis., a corporation of Wisconsin

Filed Feb. 23, 1965, Ser. No. 83,919

Term of patent 14 years

(Cl. D37—1)

FIG. 1 is a plan view of a hand grinder embodying my new design.

FIG. 2 is a side elevational view thereof.

FIG. 3 is a rear end elevational view thereof.

FIG. 4 is a front end elevational view thereof.

FIG. 5 is a bottom plan view thereof.

FIG. 6 is a view taken in cross section on the line 6—6 of FIG. 2.

FIG. 7 is a view taken in cross section on the line 7—7 of FIG. 2.

FIG. 8 is a view taken in cross section on the line 8—8 of FIG. 2.

FIG. 9 is a view similar to FIG. 2 showing a slight modification in which the vent openings are omitted, the

design being otherwise identical in all respects with that shown in FIGS. 1-8.

I claim:

The ornamental design for a hand grinder, as shown and described.
